THOMAS LEGGETT STURTEVANT, OF QUINCY, AND THOMAS JOSEPH STURTEVANT, OF WELLESLEY, MASSACHUSETTS, ASSIGNEES TO STURTEVANT MILL COMPANY, A CORPORATION OF MAINE.

MILLSTONE.

1,111,043.

Specification of Letters Patent. Patented Sept. 22, 1914.

Application filed November 25, 1910. Serial No. 594,196.

To all whom it may concern:

Be it known that we, THOMAS L. STURTEVANT and THOMAS J. STURTEVANT, citizens of the United States, residing, respectively, at Quincy and Wellesley, in the county of Norfolk and State of Massachusetts, have invented or discovered certain new and useful improvements in Millstones, of which the following is a specification, reference being had therein to the accompanying drawings.

This invention relates to that class of composite millstones comprising blocks of rock emery or other suitable hard abrasive material held in place by a metallic filling in which the abrasive blocks are embedded and which metallic filling is applied in a molten condition, so that the blocks will be strongly embedded therein. Composite millstones, of the class referred to, are well adapted for rapid grinding, in that they are not damaged by heat generated by running the stones at a high speed, as are French bur millstones, which are solid and are liable to crack if much heated. These fast-running composite millstones, however, are very heavy and must be secured together and to their carriers with much greater strength than ordinary or solid-block millstones, owing to the great strain to which such heavy stones are subjected in rapid grinding.

In carrying the present invention into effect the composite millstones comprise wedge-shaped or tapering metal blocks at their back peripheral portions and which blocks are bolted or otherwise strongly attached to one of the bands or hoops with which these millstones are provided, and are also set deeply into the metal filling of the stone; and the invention in its preferred form will also comprise wedge-shaped or tapering blocks or blocks of a strongly holding shape located between the peripheries of the composite millstones and their central portions and providing means for strongly securing the millstones to their carriers, and also for securing the back hoop or band to the millstone. These wedge-shaped or tapering blocks of any holding shape are so disposed that their wider or holding portions are toward the grinding faces of the millstones, and as they are embedded in the metallic filling which also holds the grinding blocks in place they afford

greatly increased strength for securing the bands to the millstones and the millstones to their carriers, so that the strength of the millstones, as also the strength of their attachments to their carriers is greatly increased by the improved construction.

In the operation of the millstones of the class to which the present invention relates, those portions of the millstones nearest their peripheries run the fastest, so that each inch of grinding surface near the periphery of a stone is more effective, in the grinding operation, than several inches of surface near the eye of the stone where the movement is much slower. The emery blocks forming the grinding portions of these composite stones are very hard and intractable, and are of very irregular shape. Heretofore blocks have been selected so as to fill the faces of stones, near their peripheries, as nearly as possible, but owing to the irregular forms of these blocks the faces of composite millstones, as heretofore constructed, have frequently been weak and greatly lacking in continuity at their peripheral portions where the greatest grinding effect is secured. In the present improved millstone the emery blocks are shaped or formed convex on their outer faces so as to conform more or less closely in curvature to the curvature of the bands of the stones. This shaping of the blocks is more or less expensive, owing to their hard and intractable character, but the greatly increased efficiency resulting from forming these composite millstones with practically continuous grinding or emery-stone faces near their peripheral portions warrants the greater expense of construction.

In the accompanying drawings Figures 1 and 2 are face and back views, respectively, of a millstone embodying the present invention. Fig. 3 is a partial sectional view of the same. Figs. 4 and 5 are detail views of different forms of tapering or wedge-shaped blocks which may be employed.

Referring to the drawings, 12 denotes the improved composite millstone which comprises abrasive blocks 13, preferably of rock emery, embedded in a metallic filling 14 preferably poured in or around the blocks 13 in a molten condition. Also embedded in the metallic filling 14 are tapering metal blocks 15 which are preferably provided

with flanges 16 by which they may be bolted or riveted to the back band or hoop 17 of the stone, so as to be permanently attached to said band, these blocks being also preferably provided with threaded holes 18 for the insertion of screw-bolts to attach the composite millstone to its carrier. Also embedded in the metallic filling are wedge-shaped metal blocks 19, in the preferred form of the invention, these blocks 19 being arranged between the periphery of the millstone and the central portion thereof and provided with threaded openings 20 for the reception of screw-bolts to attach them to the millstone carrier. The thicker portions of these tapering or wedge-shaped blocks 15 and 19 are at their inner parts, or away from the rear face of the composite stone, so that the said blocks taper outwardly and flare inwardly, to insure a strong holding effect in securing the stone to its carrier. The blocks 15 and 19 are preferably of cast iron. The outer faces of the emery blocks 13, which are disposed near the periphery of the millstone, are preferably formed convex or curved so as to conform to the curvature of the band 17, or approximately so, thereby providing, as nearly as possible, continuous grinding faces near the peripheral or skirt portion of the millstone, or at that portion of the millstone which has the highest speed, and consequently the most efficiency, when the millstone is running.

From the foregoing it will be understood that the improved construction provides means for strongly securing the back band or hoop to the composite millstone, as also means for strongly attaching the millstone to its carrier, thereby avoiding all danger of the millstone becoming loose when in rapid rotation; while the practically continuous grinding peripheral face portion of the improved millstone will add considerably to its efficiency.

Having thus described our invention we claim and desire to secure by Letters Patent:

1. A composite millstone comprising blocks of hard abrasive material and a metallic filling in which said blocks are embedded, combined with one or more metal bands or hoops encircling the millstone, and a plurality of inwardly flaring or outwardly tapering metal blocks also embedded in the metal filling at the back of the peripheral portion of the millstone and permanently attached to one of said bands or hoops, for strongly securing the said band or hoop to the periphery of the millstone, the said blocks being also adapted for attachment to the millstone carrier.

2. A composite millstone comprising blocks of hard abrasive material and a metallic filling in which said blocks are embedded, combined with one or more metal bands or hoops encircling the millstone, a plurality of

of inwardly flaring or outwardly tapering metal blocks also embedded in the metal filling at the back of the peripheral portion of the millstone and permanently attached to one of said bands or hoops, for strongly securing the said band or hoop to the periphery of the millstone, the said blocks being also adapted for attachment to the millstone carrier, and an interior set of inwardly flaring or outwardly tapering metal blocks also embedded in the said metallic filling at the back of the millstone and adapted for attachment to the millstone carrier.

3. A composite millstone comprising blocks of emery stone, a metallic filling in which said blocks are embedded, and binding hoops or bands, said emery blocks being artificially shaped at their peripheral outer face portions to conform to the curvature of the said binding hoops or bands, or approximately so, the said millstone also comprising inwardly flaring or outwardly tapering metallic holding blocks embedded in the metallic filling at its peripheral back portions and permanently attached to one of said hoops or bands.

4. A composite millstone comprising blocks of emery stone, a metallic filling in which said blocks are embedded, and binding hoops or bands, said emery blocks being artificially shaped at their peripheral outer face portions to conform to the curvature of the said binding hoops or bands, or approximately so, the said millstone also comprising inwardly flaring or outwardly tapering metal holding blocks embedded in the metallic filling at its peripheral back portion and permanently attached to one of said hoops or bands, and other metal inwardly flaring or outwardly tapering holding blocks embedded in said metallic filling between the periphery of the stone and its central part, said metal blocks being adapted for attachment to the millstone carrier.

5. A composite millstone comprising blocks of hard abrasive material and a metallic filling in which said blocks are embedded, combined with one or more metal bands or hoops encircling the millstone, and a plurality of inwardly flaring or outwardly tapering metal blocks also embedded in the metal filling at the back of the peripheral portion of the millstone and provided with flanges by which they are permanently attached to one of said bands or hoops, for strongly securing the said band or hoop to the periphery of the millstone, the said blocks being also adapted for attachment to the millstone carrier.

6. A composite millstone comprising blocks of hard abrasive material and a metallic filling in which said blocks are embedded, combined with one or more metal bands or hoops encircling the millstone, a plurality of inwardly flaring or outwardly tapering metal

- blocks also embedded in the metal filling at the back of the peripheral portion of the millstone and provided with flanges by which they are permanently attached to one of said bands or hoops, for strongly securing the said band or hoop to the periphery of the millstone, and an interior set of tapering metal blocks also embedded in the said metallic filling at the back of the millstone and adapted for attachment to the millstone carrier.
7. A composite millstone comprising blocks of emery stone, a metallic filling in which said blocks are embedded, and binding hoops or bands, said emery blocks being artificially shaped at their peripheral outer face portions to conform to the curvature of the said binding hoops or bands, or approximately so.
8. A composite millstone comprising blocks of hard abrasive material and a metallic filling in which said blocks are embedded, combined with a metal band or hoop encircling said millstone, and holding blocks also embedded in said metallic filling at the back

of the peripheral portion of the millstone and permanently secured to said band or hoop, said holding blocks being adapted for attachment to the millstone carrier.

9. A composite millstone comprising blocks of hard abrasive material and a metallic filling in which said blocks are embedded, combined with a metal band or hoop encircling said millstone, holding blocks also embedded in said metallic filling at the back of the peripheral portion of the millstone and permanently secured to said band or hoop, said holding blocks being adapted for attachment to the millstone carrier, and interior holding blocks also embedded in said metallic filling at the back of the millstone, and also adapted for attachment to the millstone carrier.

In testimony whereof we affix our signatures, in presence of two witnesses.
